UNITED STATES PATENT OFFICE.

CHARLES H. WOODS, OF DECATUR, ILLINOIS.

FARE BOX.

Application filed August 7, 1922. Serial No. 580,103.

To all whom it may concern:

Be it known that I, CHARLES H. Woods, a citizen of the United States, a resident of Decatur, in the county of Macon and State 5 of Illinois, have invented new and useful Improvements in Fare Boxes, of which the following is a specification.

This invention has reference to fare-boxes, and relates particularly to that type of fare-box in which is deposited the coin, ticket or token by a passenger on entering a 10 street car.

The invention has for its principal object to improve that type of fare-box which is 15 provided with a removable till having a closure normally retained in an open position when in the fare-box, and which is caused to assume a closed and locked position when removed from the fare-box, by 20 providing the closure with a lock which cannot be tampered with, and suspending the till on rails which have means complementary to means on the till and the closure, whereby the till is slidably supported in 25 different horizontal planes.

The invention has for a further object to slidably support the till in a fare-box on rails having means complementary to means 30 on the till and its closure, whereby the till is slidable in different horizontal planes when placing and removing the same, and providing for the opening of the closure for the till when placing the same in the fare-box, and for automatically closing the 35 till during the withdrawal of the till and for locking such closure at or about the moment the till changes from one horizontal position to another.

A further object of the invention is to provide 40 a till for fare-boxes having a partial fixed closure and a coacting closing member slidable in relation thereto; and locking means between the fixed and slidable closing elements at a point mediate the front and back of the till, whereby tampering with the locking means is made impracticable.

A further object of the invention is to provide 45 the fare-box with supplemental locking means for the door or hinged cover, in addition to the key-lock, said supplemental locking means being hidden from view within the fare-box and may only be actuated through the actuation of the dumping plate located between the container and depository 55 of the fare-box.

That the invention may be more fully

understood, reference is had to the accompanying drawings, forming a part of the description, illustrating a preferred embodiment of the invention, in which:—

Figure 1 is a front elevation of a fare-box on a greatly reduced scale, partly in section, embodying my invention;

Figure 2 is a vertical sectional detail view as the same would appear if taken on the line 2—2 Figure 1;

Figure 3 is a detail section in plan as the same would appear if taken on the line 3—3 Figure 2;

Figure 4 is a detail side elevation of the 70 supporting means for the till, the latter in position with the closure in open position;

Figure 5 is a plan view partly in section of the parts and as they appear in Figure 4;

Figure 6 is a view similar to Figure 4 except that the till has been withdrawn to a 75 position which will close the closure of the till;

Figure 7 is a view similar to Figure 6 except that the till has been lowered on its 80 supporting means or changed from one horizontal position to another, preparatory to withdrawing the till from the fare-box;

Figure 8 is a plan view partly in section of the parts, as they appear in Figures 6 85 and 7;

Figure 9 is a view similar to Figure 7 except that the till is shown having been removed from its supporting means, and

Figures 10, 11 and 12 show a side elevation, end view and plan of the till supporting means.

Like characters of reference denote corresponding parts throughout the figures.

The fare-box comprises in the main, a 95 container supporting a depository for the coins, tickets or tokens and separated by a dumping-plate; a till or receiving receptacle adapted to be removably housed in the container and having a lid or slide-cover which, 100 when the till is placed in the fare-box is opened and when the till is removed from the fare-box the slide-cover is closed, and to other and minor details to be hereinafter more particularly referred to.

The container.—This is preferably made in the form of an upstanding rectangular box 1, having four side walls, one of which includes a door 2 hinged at 3 to a corner of the box so that it may be swung open and shut to allow for the removal and placing of the till or receiving receptacle. A key-lock

4 is provided at the swinging edge of the door that it may be locked when closed. It is further provided to lock the door within the container by supplemental locking means which is hidden from view and which may be unlocked through the actuation of the dumping plate, as will be described. This supplemental locking means, includes a socketed member 5 secured to the inside face of the door 2 and near its upper edge. To the inside face of the front wall of the container is secured a tubular member 6, the axis of which coincides with the axis of the member 5 when the door is closed. Slidable in said member 6 is a spring held plunger rod or stem 7 provided with a finger 8 movable in a slot 9 in the wall of the member 6.

The container 1 is capped by a casting 10 formed with a hopper shaped inlet 11 and recesses or grooves 12 to receive the walls of the depository, and depending within the casting from its top wall is a hopper shaped neck 13 the front wall of which is removed, see Figure 2 to permit movement of the means on the dumping plate for actuating the plunger rod or stem 7, as will be explained.

The depository.—This is also made preferably in the form of an upstanding rectangular receptacle 14 having the metallic corner pieces 15 and connecting the corner pieces are transparent side walls 16, preferably glass, seated in the recesses 12 in the casting 10. The depository is capped by a casting 17 secured in place in any suitable manner and upstanding from said casting is a neck 18 into which the coin, ticket or token is deposited. Suitably arranged in the depository 14 are a plurality of staggeredly arranged baffle-plates 19 with notched lower edges 20.

Normally lying across and closing the lower end of the hopper shaped inlet 11 of the casting 10 is a dumping plate 21 which is suitably secured at its front side to a spindle 22, one end of which protrudes through the casting 10 and wall of the container and has secured thereto a handle or crank-arm 23 to be grasped by an operator when it is desired to tilt said dumping plate and also to release the supplemental locking means 7. A coil spring 24 wrapped or coiled about said spindle 22 and with a part bearing against the lower face of the dumping plate and with a part bearing against the under side of the casting 10 acts to return the dumping plate to its closed position and normally hold it closed, except when tilted in the manner and for the purpose explained. To the spindle 22 is connected an arm or finger 25, adapted when the spindle is oscillated to be brought into engagement with the finger 8 on the rod or stem 7 to raise and release the latter from the socketed member 5 on the door 2.

The till or receiving receptacle.—This is preferably a metallic box 26 which, in shape, conforms to the contour of the container 1, having a hand hold 27 to be grasped by an operator when removing the same from the container, or replacing it. The upper end of the till or receiving receptacle is capped by a casting 28 formed with a dividing partition or closure 29 extending the full width of the casting, in one direction, and only approximately one-half way across in the other direction so as to provide an opening 30 through which coins, tickets or tokens may pass when entering the till and dumped by the dumping plate 24. The inner end of said partition or closure 29 is bent up, as at 31, to provide a stop as well as a coacting element of the lock on the movable slide or closure, to be described. Said bent up portion 31 of the partition or closure 29 is slotted as at 32 through which the lock, to be described, slides. In the opposite side walls of said casting 28 are provided longitudinal grooves 33 and also in the opposite side walls of said casting and extending longitudinally thereof from the rear to a suitable point mediate the front and back, are provided the slots 34.

35 designates a slidable closure for the opening 30 in the till. It is supported to slide back and forth in the grooves 33 and at its front end has the depending plate 36 which moves next adjacent to the bent portion or stop 31 of the partition 29 when said slide 35 is closed, the forward movement of the slide being limited by engagement of lugs 37 projecting from said slide through the slots 34 in the till, with spring held pawls 38 pivoted to rails or castings 39 secured to the opposite inside walls of the container 1. The rails 39 have lips or ears 40 by means of which they may be bolted or otherwise secured to the walls of the container 1. Each rail is provided with grooves a, b and c which have communication through a passage way d which intercepts the groove b which is longer than the grooves a and c. Normally the acting ends of the pawls 38 lie in the grooves a being yieldingly held in such position by means of springs 41 contained in barrels 42 on said rails or castings 39. To the inner end of the slide 35 and to the under side thereof is secured locking means 43 controllable by a key-barrel 44 on the upper side of said slide. The locking means, when the slide is open or in its forward position lying within the slot 32 in the stop 31 and when the slide 35 is closed said locking means is disposed behind said stop 31 with the active elements of the locking means spread out against the stop 31. In this position the locking means for the slide is entirely hidden and tampering with the same is not possible. A key fitted to and inserted in the key barrel 44

will release the locking means to permit the slide 35 to be moved into the open position shown in Figure 2. The details of the lock are not shown, as it is not intended to claim 5 the same specifically herein. It is intended, however, that when the slide 35 is moved to closed position, the lock acts automatically to lock the slide 35 in closed position, and the slide 35 may not be opened until the 10 insertion of a key into the key barrel 44 and the locking means is released.

The casting 28 of the till is provided with a plurality of lugs 45, 46 and 47 which project from the opposite sides of the said 15 casting. Said lugs lie in the same horizontal plane and suitably spaced from each other, but preferably in a horizontal plane below the slots 34, and the lugs 37 on the slide 35.

20 When assembling the fare-box, the rails or castings 39 are secured in place with the open ends of the grooves *a*, *b* and *c* in said slides adjacent the opening in the container, closed by the door 2, see Figure 2. Assuming that the door is open and it is desired to insert the till, the lugs 45 are inserted into and caused to be moved rearwardly in opposite grooves *b* of the rails or castings, and the lugs 37 are inserted into 25 and caused to be moved rearwardly in the opposite grooves *a* of the rails or castings, and when said lugs 37 reach the pawls 39 they ride beneath the same, raising said pawls against the tensions of the springs 30 42 which act to force said pawls down in front of the lugs 37 as soon as they have passed thereunder, see Figure 6. The rearward movement of the till is then continued until the lugs 45 reach the extreme inner 35 ends of the grooves *b*, while at the same time the lugs 46 and 47 have entered and become positioned in the grooves *b*, see Figure 4. During this last mentioned rearward movement of the till, the lugs 37 are held, as shown in Figure 4 causing the 40 slide 35 to be held in position, with the till moving thereunder until the opening 30, closed by the till, is exposed to the dumping plate 21 to permit coins, tickets or tokens deposited to be passed down through the opening 30 into the till. The foregoing movements have been described as taking 45 place, assuming that the locking means has been released so as to permit the till to be moved relatively to the slide 35, after the lugs 37 and 45 have reached the passageway *b* and the till raised to change the horizontal position of the lugs 45, 46 and 47, as well as the lugs 37.

50 Assuming now that the till is in receiving position in the container, see Figures 2, 4 and 5 and it is desired to remove the till from the container and during such movement close the slide 35 over the opening 30 and lock it in such closed position. The op-

erator will unlock the door 2 at 4 and grasp and oscillate the hand hold 23 lifting the finger 25 into engagement with the finger 8 and release the locking member 7, permitting the door 2 to be swung into open position. The door 2 being opened, the operator will then grasp the hand hold 27 on the till and draw the latter outwardly the lugs 45, 46 and 47 moving forwardly in the grooves *b*, until the lugs 46 have cleared the ends of the rails or castings 39, see Figures 6 and 7 and the lugs 45 are brought into coincidence with the passageway *d*, see Figures 6 and 7, when the till will drop positioning the lugs 45 in the grooves *c* and the lugs 46 75 and 47 in line therewith, see Figure 7. During the movement of withdrawing the till with the lugs 45, 46 and 47 moving forwardly in the groove *b*, the lugs 37 on the slide 35 are held by the pawls 38 against 80 forward movement, resulting in the till moving forwardly under the slide 35, or in other words, moving relatively thereto, and when the lugs 45 reach the passageway *d* the slide is closed and the lugs 37 and 45 are in superimposed position, see Figures 6 and 7. In this position the locking means 43 is locked against the rear face of the stop 31 on the plate or closure 29. The till having been lowered, as described, a further withdrawal 85 movement will cause the lugs 37 to pass out through the grooves *b* in the rails or castings 39, and the lugs 45 to pass out through the grooves *c* in said rails or castings, as it is believed will be understood. The withdrawal 90 movement of the till being graphically illustrated in Figures 7 and 9.

The till being suspended from the rails or castings 39, it will be obvious that when the lugs 45 reach the passageways *b* during the 105 withdrawal movement of the till that the till will drop of its own weight positioning the lugs 45 in the grooves *c*, and the lugs 37 in the grooves *b*. To insert the till the lugs 37 pass through the grooves *a* under and behind the pawls 38 and the lugs 45, 46 and 47 110 enter the grooves *b*.

To the rear wall of the container 1 are secured cleats 50 for supporting the fare-box from a post, bracket or other suitable means 115 in a street car.

From the within disclosure it will be observed that I have provided a fare-box including a till, the supporting means for which and the closure are simple, yet effective. Being simple in construction and with nothing to get out of order, and so constructed as to stand rough treatment without disturbing the operating parts. While I have elected a preferred embodiment of the invention I am fully aware that modifications may be made within the range of skilled mechanics and therefore, do not wish to be confined to the details disclosed, except as stated in the appended claims. 120 125 130

What I claim is:—

1. In a fare-box, in combination, a container, a till, a slidable closure for said till, grooved supporting rails secured to opposite walls of the container, means on the till and its closure adapted to have a slidable relation with said grooved rails, and means on said rails to retard the movement of said closure as the till is withdrawn and until the closure assumes a locked position.
2. In a fare-box, in combination, a container, a till, a slidable closure for said till, supporting rails secured to opposite walls of the container and provided with corresponding superimposed communicating grooves opening out of one end of said rails, means on the till and its closure adapted to have a slidable relation with certain of said grooves when said till is inserted into said container and other of said grooves when said till is removed from said container, and means on said rails to retard the movement of said closure as the till is withdrawn and until the closure assumes a locked position.
3. In a fare-box, in combination, a container, a till, a movable closure for said till, guiding and supporting means for the till in the container, means on the till and its closure adapted to have a coacting relation with said guiding and supporting means, the latter being arranged for the insertion and removal of the till in different horizontal planes, and means to hold the closure relative to the till as the latter is withdrawn and until the closure assumes a locked position.
4. In a fare-box, in combination, a container, a till provided with a pair of oppositely disposed slots, a slidable closure for said till, lugs on said closure operating in and through said slots, other lugs projecting from opposite sides of said till, supporting means for the till provided with grooves, certain of which are adapted to receive the lugs on the till and closure when the till is inserted into the container and others of which are adapted to receive said lugs when the till is withdrawn, and means to hold the closure relative to the till as the latter is withdrawn and until the closure assumes a locked position.
5. In a fare-box, in combination, a container, a till, a slidable closure for said till, lugs on the closure, lugs on the till, guiding and supporting rails secured within the container and provided with a plurality of superimposed grooves intercepted by a transverse passageway, the lugs on the till and the closure adapted to travel certain grooves in said rails when the till is insert-
- ed and travel certain other grooves and said passageway when the till is withdrawn, and pivoted pawls under and behind which said lugs on the closure move as the till is inserted for retarding the closure during the withdrawal of the till and until the closure assumes a locked position.
6. In a fare-box, in combination, a container, rails secured to opposite inside walls of said container, each of said rails provided with a plurality of superimposed grooves opening out of one end of said rails and a passageway intercepting the middle groove and communicating with the upper and lower grooves, yieldingly held pawls lying within the upper grooves of each rail and at the inner ends thereof, a till, a slidable closure therefor, lugs on said closure and a plurality of lugs on said till, the lugs on the closure movable in the upper grooves and the lugs on the till movable in the middle groove when the till is inserted into the container, and the lugs on the closure movable in the middle groove and the lugs on the till movable in the lower groove when the till is withdrawn, said pawls acting to retard the closure during the withdrawal of the till and until the closure assumes a locked position.
7. In a fare-box, in combination, a container, a till, a fixed cover for a portion of the upper end of said till and provided with an inner upstanding stop slotted mediate its ends, a slidable closure for the open space at the upper end of said till and provided with a depending flange at its front end, locking means secured to said slidable closure and movable through the slot in the fixed cover portion and adapted to coact with said top, means in the container to suspend said till, and means to retard the slidable closure during the withdrawal of the till and until the slidable closure assumes a closed position.
8. In a fare-box, in combination, a container, a door hinged to said container, locking means for said door located wholly within said container, a dumping plate within the container, means located without the container for actuating said dumping plate, means associated with said dumping plate for releasing said locking means, a till, means in the container with which the till has a slidable relation, a slidable closure for said till, and means to automatically close and lock said closure as the till is withdrawn from said container.

In witness whereof, I have hereunto affixed my hand.

CHARLES H. WOODS.
